(57) **CLAIM**

The ornamental design for a scratching tool, as shown and described.

DESCRIPTION

FIG. 1 is a top isometric view of the scratching tool according to one embodiment;

FIG. 2 is a side elevation view thereof;

FIG. 3 is a top view thereof which is a mirror image of the bottom view;

FIG. 4 is a first end view thereof;

FIG. 5 is a second end view thereof;

FIG. 6 is a top isometric view of the scratching tool according to an alternative embodiment;

FIG. 7 is a side elevation view thereof;

FIG. 8 is a top view thereof which is a mirror image of the bottom view;

FIG. 9 is a first end view thereof; and,

FIG. 10 is a second end view thereof.

The gripping portions are shown in broken lines in FIGS. 1-10 for illustrative purposes only and form no part of the claimed design.
